COMBINATION GATE AND BY-PASS VALVE.

1,020,159.

Specification of Letters Patent. Patented Mar. 12, 1912.

Application filed July 5, 1906. Serial No. 324,873.

To all whom it may concern:

Be it known that I, ALFRED PRICE, a citizen of the United States, residing at Los Angeles, in the county of Los Angeles and 5 State of California, have invented a new and useful Combination Gate and By-Pass Valve, of which the following is a specification.

It is of the objects of this invention to 10 provide for high pressure water and steam pipes a gate or valve which can be readily opened and closed; which will wedge tightly in place at the final closing movement of the gate-spindle, and which will readily be 15 come freed from any clogging material.

A further object is to provide a simple and compact gate by which the foregoing objects are accomplished.

The accompanying drawings illustrate 20 the invention:—

Figure 1 is a sectional elevation on the axial line of a straight way gate embodying my invention. The valve-spindle and other parts are shown in the position occupied at 25 the final closing movement of the by-pass plates or disks just after the valve plates or disks have come into position to be finally seated by the wedging movement of the valve-plate operating means. The position 30 of the parts shown is much the same as that which they assume at the initial opening movement after the by-pass valve plates have been unseated. The openings between the valve disks or plates and their seats are 35 exaggerated. Fig. 2 shows a like section of the valve-shell with an elevation of the edge of the valve in place; the by-pass disks are seated and the valve and by-pass disks are wedged home. Fig. 3 is a fragmental plan 40 section on line x^3 , Fig. 1. Fig. 4 is an elevation of the plate-operating means, a by-pass valve-disk and a valve-disk in assembled position. Fig. 5 is a view of the face 45 of the by-pass valve-disk which engages the disk-operating means. Fig. 6 is a view of the inner face of one of the valve-disks.

1 designates the valve body provided with a gate-way 2.

3 is a valve-gate comprising two perforated valve-disks or plates 4 mounted in said way 2 and provided on their adjacent faces with by-pass valve-seats 5.

6 designates two perforated by-pass valve plates seated in said by-pass valve-seats 5

for controlling the perforations of said 55 valve-disks.

8 designates the valve-plate operating means, the same being in the form of a double wedge-shaped head for moving the by-pass plates 6 to open and close the by- 60 pass slots or perforations of the gate. 9 designates the by-pass perforations in the valve-disks, and 10 the by-pass perforations in the by-pass disks.

11 designates a spring mounted in ways 65 12 in the valve-disks 4 to engage the head 8 on the downward movement of said head, and to hold said head from wedging the by-pass valve-plates apart until said head is forced down at the final closing movement 70 of the valve. The spring 11 may be a resilient plate mounted in the ways 12 which allow the valve disks or plates to have a play toward and from each other for seating and unseating the valve. 13 is the spindle 75 which operates the head 8, and 14 is a wheel for operating said spindle.

The head 8 is provided with shoulders 15, and the by-pass valve-plates 6 are provided with shoulders 16 to be engaged by the 80 shoulders 15, and the wedging faces 17 to be engaged by the wedge-shaped head 8.

The valve-disks 4 are provided with portions 18 which engage each other to prevent the disks from binding on the nut 19 or legs 85 20 of the head 8.

It is to be understood that any means may be employed for forcing the head up or down. In the drawings, the usual screw-threaded spindle 13 is shown. 90

In practical operation, assuming the valve to be closed, as shown in Fig. 2; the attendant may open the same by rotating the wheel 14 raising spindle 13, thereby moving the head 8 from its wedging position shown in Fig. 2 to its lifting position shown in Fig. 1. Upon further upward movement of the operating head 8 the by-pass valve-plates will be moved to admit water through the ports 9, 10, thereby equalizing the pressure on the valve sufficiently 95 to allow the same to be moved by application to the spindle of a moderate degree of force. At the same time, the valve-plates are relieved from the wedging stress and the 100 valve-plates become unseated from the main valve-seats 21 in the shell or body 1 of the valve. A further upward movement of the 105

head 8 acts through the by-pass valve-plates 6 to lift the valve-disks or plates 4 to open the way 22 for the passage of steam, water or other fluid.

To close the valve, the operation is reversed and the head 8 will lower until the valve-plates 4 are seated in the seat 23 in the valve shell or body 1, whereupon the valve-plates or disks come to rest, and upon the further downward movement of the valve-operating head 8, the by-pass valve-plates 6 will be forced downward by engagement of said head, and the downward stress of the head will act upon the spring 11 until the head is lowered far enough to force the by-pass valve-plates into closed position, and to spread said plates and the valve-plates 4. Whenever the stem 13 moves downward it carries the wedging member or head 8 downward, and as said wedging member moves downward the gravity of the valve-plates will cause the same to move downward unless obstructed from some cause, and in case of any such obstruction, as by partial seating of the valve-plates, the engagement of the head 8 on the spring 11 will transmit force from the stem 13 to the plates 4 to move them downward.

The spring 11 is preferably bowed upward when free, and when the head engages the same there may be considerable downward movement of the head before the wedging movement begins.

On the upward movement of the head 8 the shoulders 15 operate through shoulders 16 of the by-pass valve-plates 6, which plates are lifted thereby, to lift the shoulders 24 of the main valve-plates 4; and in this manner the main plates 4 are lifted after the by-pass has been opened and the pressure relieved, so that said main valve-plates may be lifted with comparatively small friction relatively to the valve-seats of the shell 1.

On the closing movement, the gravity of the valve-plates or pressure of the head 8 on spring 11 will carry the same onward until said plates are seated in the seat 23, whereupon a further closing movement will cause the wedges to force the by-pass valve-plates tightly against the main valve-plates.

The perforations in the main and by-pass valve-plates 4 and 6 are preferably in the form of elongated slots, as shown, whereby a slight movement of the by-pass valve-plates opens a considerable area for the flow of the fluid for equalizing the pressure.

The spring 11 may be held in place by a pin 25 at one end, while the other plays freely in the way 12.

In case the valve is mounted with the stem 13 hanging down, the head will lift the valve-disks and plates through direct contact therewith and through the spring 11. This will readily be understood by simply inverting the drawings. It is advisable

to employ the spring as shown in order to insure the closing movement. It is thus seen that the wedge means is in operative relation to the valve-plates being operable through the medium of its shoulders and the by-pass plates to lift the valve-plates, and is also operable through the medium of the spring 11 to hold the valve-plates down during the period between the release of the wedge and the uplifting of the valve-plates.
